CLAIM

I claim the ornamental design for a laboratory table top, as shown.

DESCRIPTION

FIG. 1 Is an isometric view of the laboratory table top.

FIG. 2 is a top elevational view of the laboratory table top of FIG. 1.

FIG. 3 is a bottom elevational view of the laboratory table top of FIG. 1.

FIG. 4 is a front elevational view of the laboratory table top of FIG. 1.

FIG. 5 is a right side elevational view of the laboratory table top of FIG. 1; and,

FIG. 6 is a rear elevational view of the laboratory table top of FIG. 1.

1 Claim, 4 Drawing Sheets

FIG. 1

FIG. 2

FIG. 3

FIG. 4

FIG. 5

FIG. 6
